DENSITY RESPONSIVE DEVICE

Elmer A. Haase and Jay A. Bolt, South Bend, Ind.,
assignors to Bendix Aviation Corporation, South
Bend, Ind., a corporation of Delaware

Application March 6, 1944, Serial No. 525,278

2 Claims. (Cl. 236—92)

1

This invention relates to a density-responsive control unit of the corrugated single capsule type and to the method of constructing the same.

Units of the type with which the present invention is concerned are particularly useful in carburetors for aircraft internal combustion engines to automatically adjust the fuel/air ratio of the fuel mixture supply in accordance with changes in pressure and temperature, such as are experienced at varying altitudes. A unit of this type may, for example, be used in a carburetor to control the area of the fuel metering orifice to thereby control the fuel/air ratio; or it may be used to modify the air metering differential pressure used in regulating the fuel flow to thereby vary the fuel flow and consequently the fuel/air ratio; or it may be used in other ways to control the ratio of fuel and air being supplied by the carburetor to the engine.

An object is to provide a density-compensating unit of the single bellows or capsule type having certain features of construction which result in improved performance characteristics.

Another and more specific object is to provide a density control capsule or bellows embodying a valve element which will be automatically moved to a "safety" position in the event of bellows failure.

Other objects and advantages will become apparent in view of the following description taken in conjunction with the drawings, wherein:

Figure 1 is a view principally in substantially central vertical section of an injection-type carburetor having the improved control unit of the present invention operatively applied thereto;

Figure 2 is a transverse vertical section of the control unit of Figure 1;

Figure 3 is a top plan of Figure 2; and

Figure 4 is an enlargement of the lower portion of Figure 2.

The construction of the improved control unit per se will first be described, next the method of filling the same, and finally its adaptation to, and operation in connection with the injection type carburetor of Figure 1.

Referring particularly to Figures 2, 3 and 4, the unit comprises a corrugated bellows 10 which at its upper extremity is secured in leak-proof relation, as by soldering, to a flange 11a forming part of an externally threaded head or cap 11, and at its lower extremity is secured in a like manner to a flange 12a forming part of a closure and valve-carrying member 12, the latter having a dash-pot cylinder 13 projecting upwardly therefrom over which is mounted a spring

14, abutting at its lower end against a shoulder 12b forming part of member 12 and at its upper extremity against the top transverse wall 15 of cap 11. The spring 14 prevents collapse of the bellows when the latter is evacuated, as will be more fully hereinafter explained.

A combined dash-pot piston and guide member 16 is inserted in an opening formed in the end wall 15 of cap 11 and has a flange 17 secured in leak-proof relation thereto. The lower extremity 16a of the member 16 has a sliding fit in the cylinder 13 and functions as a dash-pot piston with respect to said cylinder and also as a guide for the bellows. The member 16 is formed with a fill port 18 which connects with a cross-port 18a communicating with the interior of the bellows 10, the upper extremity of the port 18 being enlarged and internally threaded to removably receive a sealing plug 18b. The body of the piston 16a is preferably formed with a relieved portion indicated at 19 to facilitate lubrication of the side walls thereof.

The top wall 15 of head or cap 11 may be provided with a plurality of fins 20 which render the device more sensitive to changes in temperature in that they expedite transmission of heat to the wall 15 and thence to the interior of the cap, the latter preferably being filled or partly filled with a temperature-responsive medium other than air in a manner to be described.

At its lower extremity, the cylinder 13 is formed with one or a plurality of restricted ports 21, whereby oil or other damping fluid is permitted to pass from said cylinder into the bellows and return when the bellows is compressed and extended and relative reciprocatory movement ensues between the piston and cylinder, to thereby more effectively damp vibration of the bellows.

The parts thus far described constitute a bellows assembly which is carried by a housing 22, the latter at its lower extremity being threaded into a supporting bushing 23 provided with a lock nut 24, said bushing having a lower projection or boss 25 adapted to be threaded into a socket provided therefor in a stationary support, such as the deck or top wall of a carburetor, note Figure 1.

A valve member or needle 26 is carried by the movable end of the bellows, said needle at its upper end being secured to an annular disc 27 which rests on a retaining washer 28 removably held in place by a resilient snap ring 29 adapted to engage in a groove formed in the inner wall of the member 12. A plunger 30 is inserted in a bore formed in the upper extremity of the needle 26

and is normally urged against the bottom wall of the member 12 by a spring 30a, to thereby resiliently maintain the said valve in its assembled position and permit self-alignment.

The needle valve 26 is preferably of the "slab" type and is slideable within a sleeve 31 having a press fit in a bore formed in the central portion of bushing 23, the lower end of the said needle preferably being tapered or beveled and cooperating with a transverse port or passage 32. An overtravel by-pass port or slot 33 is formed in one side of the needle and functions as a safety means in the event the bellows should break, as will be more fully hereinafter described.

A lock nut 34 is threaded over the cap 11 and contacts the upper end of housing 22, to ensure against displacement of the bellows and coacting parts.

A seat member 35 is provided at the lower end of the boss 25 and has an external annular groove adapted to receive a sealing gasket when the unit is mounted as shown in Figure 1.

The unit herein illustrated is of the venturi-vented type, and accordingly the bushing 23 is formed with air-inlet vents or ports 36 which communicate the bellows with the main venturi of the carburetor, calibrated ports 36a in the upper extremity of the bellows housing communicating the bellows with the air scoop. This places the bellows in pressure communication with the air flowing through the venturi as well as the air in the region of the carburetor deck whereby the bellows is subjected to a pressure intermediate the pressures in the venturi and scoop. This reduces the error which would otherwise result from the change in pressure and hence density which occurs due to change in velocity. The arrangement of ports 36 and 36a at opposite ends of the housing 22 also induces circulation of air in the bellows housing, and improves the rate of responsiveness of the bellows to changes in temperature of the air entering the scoop.

The manner in which the capsule is charged or loaded, and its spring rate per given size or unit capacity are factors which have an important bearing on the temperature and density compensating characteristics and accurate metering of the unit. Theoretically, a bellows with no spring force or effect exerted at any time would result in substantially similar internal and external pressures and travel of the needle valve or element controlled thereby in direct relation to density for any temperature, but from a practical standpoint, this cannot be achieved. In the present invention, a bellows is used having a relatively low spring rate per unit capacity or for a given stroke of the bellows, and the error remaining due to spring effect is offset by predetermined evacuation. By "stroke" is meant the axial travel or movement of the bellows to carry the needle valve over the range of movement it must have to properly control the valve port. Spring rate of the bellows is influenced primarily by the number of active corrugation per given stroke, wall thickness of the bellows, and type of material from which the bellows is made. The stroke that a given size bellows will have under load is directly proportional to the number of active corrugations and inversely proportional to some power of wall thickness. In the example illustrated in Figure 2 of the drawings, the bellows has eleven active corrugations with side walls of beryllium copper of single ply thickness. However, when spring rate is reduced beyond a certain point, a problem presents itself in that the

bellows tends to become unstable in operation, particularly during the time it passes from a state of expansion and begins to contract, as where it moves from a high to a lower altitude. To more accurately control the travel of the bellows, a larger quantity of oil or other damping fluid is used than is the case with bellows having less flexibility. This has a stabilizing influence and has given satisfactory results.

Another important factor to be considered is the degree of evacuation of the bellows. According to the present invention, the bellows is evacuated at ground level barometer to an internal pressure equivalent to some external pressure which prevails at a relatively high altitude, for example, to a pressure approximating those prevailing at an altitude of 20,000 feet and which would be in the neighborhood of 14" Hg absolute pressure. Thus, when a bellows evacuated in this manner is used for a control on an aircraft carburetor, up until the time external pressures drop to a certain point, the internal gas pressure of the bellows is less than the external pressure thereon. When so evacuated and with coordinated spring loading, the major part of the effective stroke of the bellows will take place while the bellows is in compression and the minor part while the bellows is in tension. This may be controlled by greater or less evacuation with coordinated spring loading, depending upon the installation or the type of airplane to which the unit is adapted. As long as the bellows operates in a state of compression, the error introduced by spring effect is negligible. It should be understood, however, that a spring-loaded bellows evacuated at ground level to a pressure corresponding to that existing at some particular altitude will not necessarily have an internal pressure equal to such altitude pressure when that particular altitude is attained, since the internal volume of the bellows is constantly changing with changes in altitude. Hence, the internal pressure might be materially less than external pressure at 20,000 feet altitude, and the point where internal and external gas pressure become equal be considerably beyond such altitude.

Evacuation coordinated with spring rate and oil fill must be maintained within certain limits, else the unit will have insufficient temperature response and there will be increased error in this direction. Furthermore, evacuation beyond a certain point requires an unduly heavy spring to maintain the bellows in the desired state of compression at ground level barometer which introduces an error in density compensation in the region of low altitudes. Experiments have indicated a lower limit of pressure within the bellows at ground level of within the neighborhood of 10" Hg absolute pressure.

Instead of considering the degree of evacuation in terms of internal absolute pressures, it may be given as the amount of internal depression. Thus with a barometric pressure of 29.5" Hg, an internal depression of 12.0" Hg would correspond to 17.5" Hg absolute internal pressure, an internal depression of 15.75" Hg to 13.75" Hg absolute internal pressure, an internal depression of 22.5 to 7" Hg absolute internal pressure, etc.

As far as the upper limit is concerned, here the line need not be so sharply drawn. Obviously, the less evacuation, the less will be the range of bellows travel in compression and the more the range of travel in tension.

When a bellows is evacuated as above set forth,

it becomes necessary to prevent undue collapse thereof, or to maintain it in a predetermined state of compression. This is accomplished by the spring 14, which should be of such strength as to maintain the bellows in the desired condition of collapse or compression at ground level, or under pressure conditions approximating ground level.

Before being evacuated, the bellows is loaded with a certain quantity of damping fluid, preferably a good grade of petroleum oil. A certain ratio of damping fluid and temperature-responsive gas must be observed. The amount of fluid determines the enclosed gas volume, and since oil (if used) is affected by temperature, it will tend to give additional temperature compensation in the compression travel of the bellows and less temperature compensation in the extension travel of the bellows.

Figure 1 illustrates an adaptation of the improved control unit to an injection type carburetor, only such parts of the latter being shown as will permit an understanding of the operation of the unit. Briefly, the carburetor comprises a casing or housing, generally indicated at 31, having a main venturi 38 and a small or boost venturi 39. Air pressure differential chambers are indicated at 40, 41 and fuel pressure differential chambers at 42 and 43. Chambers 40 and 41 are separated by a flexible diaphragm 44, while chambers 42 and 43 are separated by like diaphragm 45. A rigid wall 46 separates chambers 41 and 42 and also serves to support a fuel-inlet valve assembly mounted for reciprocatory movement in the center of the respective chambers and adapted to move in relation to the movement of the diaphragms 42 and 43 to open a fuel-inlet port, not shown, for admitting unmetered fuel into the chamber 43, from which it flows to a regulator section, also not shown, through various metering orifices, not shown, to a discharge nozzle 49. The chamber 42 is subjected to metered fuel pressure, or in other words to the pressure of the fuel posterior to the metering orifices. The fuel metering differential pressure is thus applied across the diaphragm 45.

The chamber 40 is connected to the air scoop by means of impact tubes 51, annular chamber 52, passage 55 controlled by needle valve 26, and thence by way of passage 53; and chamber 41 is connected to boost venturi 39 by means of passage 54. When the engine is in operation, air is drawn in through the air scoop and thence through the venturis 38 and 39 and a differential pressure is created between the throat of venturi 39 and the air inlet which, at constant entering air density, is proportional to the square root of the quantity of air flowing. These respective pressures are transmitted to chambers 40 and 41 and create a net force on diaphragm 44 tending to move valve assembly 47 to the right, or in a direction to open the valve. If this force were unopposed, the valve would move to the extreme right; however, when the valve opens, fuel under pressure flows into unmetered fuel chamber 43, through the metering orifices, and thence to the discharge nozzle 49 from which it is discharged into the air stream flowing to the engine. The fuel metering differential pressure across the metering orifice resulting from or accompanying the flow therethrough, is transmitted to chambers 43 and 42, and acts upon diaphragm 45 creating a force tending to move the fuel inlet valve to the left, or in a direction to close the valve, thus opposing the force created on diaphragm

44 by the air differential pressure. The valve will therefore adjust itself to a point of equilibrium such that the differential pressure across the fuel metering orifices is equal to the differential pressure between the air inlet and boost venturi 39, whereby constant fuel-air proportioning is maintained. As engine speed is decreased, the rate of air flow through the venturi decreases, thereby decreasing the differential pressure acting on diaphragm 44, causing valve 47 to move towards closed position and thus decreasing the fuel flow to compensate for the decreased rate of air flow. Rate of fuel flow is thus directly controlled by the rate of air flow, and a constant mixture of fuel and air obtained.

For a more comprehensive disclosure of the injection carburetor disclosed in Figure 1, reference may be had to the copending application of Frank C. Mock, Serial No. 202,206, filed April 15, 1938, Patent No. 2,390,658.

Since the venturi to air scoop differential pressure increases for a given mass rate of air flow upon decrease in entering air density, the differential pressure across diaphragm 44 will tend to increase thereby increasing the fuel flow and enriching the mixture. In order to prevent such enrichment with increase in altitude, the carburetor of Figure 1 is provided with a calibrated bleed 56 interconnecting chambers 40 and 41 which is substantially ineffective to vary the pressures in chambers 40 and 41 at such times as the needle 26 is an open position, as at ground level, but which becomes increasingly effective in reducing the pressure in chamber 40 as the density responsive needle 26 progressively restricts passage 55 with increase in altitude. As a consequence, for any given mass air flow the needle 26 will so restrict passage 55 with variation in altitude that the differential in pressures across diaphragm 44 remains constant notwithstanding that the differential in the pressures at venturi 39 and impact tubes 51 increases with decrease in entering air density. By this means, automatic altitude compensation is obtained and the richness of the mixture is unaffected by variations in altitude, as is desired.

For example, as the density of the entering air decreases, as by an increase in altitude or rise in temperature, the air differential created by the main and boost venturis increases for a given weight of air and tends toward enrichment of the fuel mixture. However, such decrease in density acts on bellows 10, which expands and causes the needle valve to lower and restrict passage 55, thereby reducing the differential across the diaphragm 44 and the fuel valve tends to close and regulate fuel flow in proper ratio to mass air flow. Upon an increase in density, as where the plane descends from a high to a low altitude, the reverse takes place. The fuel mixture is thus maintained at all altitudes at the proper richness or value.

Bellows failure is very rare, but should such occur, the needle valve 26 will immediately be projected to the position shown in Figure 4, where instead of closing off passage 55 from passage 53, and thereby greatly leaning the mixture, the slot 33 provides an air by-pass around the needle valve of such flow capacity as will result in a metering pressure on the fuel jets providing a mixture ratio at least equal to that normally attained at near ground level. In other words, slot 33 may be of a capacity corresponding to the air-flow capacity past the needle valve obtained when at low altitudes, thereby providing an automatic

emergency setting which will give the pilot time to ground the plane without engine failure due to severe leaning out of the mixture.

It will be noted that the heat transfer fins 20 are located at a point where maximum heat transfer is desirable, viz., in the region of the cap containing the temperature-responsive fluid or nitrogen.

Although the invention has been described with reference to a particular embodiment, it will be understood that certain changes in construction and design as well as in the steps of the method could be adopted without departing from the scope of the invention as defined by the appended claims.

We claim:

1. A density-responsive control unit for actuating a regulating element such as a needle valve in accordance with changes in pressure and temperature over a certain altitude range including a corrugated bellows having a movable end, means connected to said latter end mounting said element, a cap at the opposite end of the bellows, supporting means to which said cap is secured, a hollow cylinder located centrally of the bellows and fixed to said movable end, a piston member projecting from said cap into said cylinder, said bellows being partly evacuated to an internal pressure corresponding to a pressure existing at an altitude well above normal ground level, a spring in said bellows encircling said cylinder and piston and functioning to sustain the bellows against abnormal collapse at ground level barometer due to evacuation, a damping fluid partly filling the bellows and a temperature-responsive inert gas filling the space above the damping fluid, said cylinder being ported to the interior of the bellows to provide a dash-pot action during extension and contraction of the bellows.

2. A density responsive device for controlling a valve arranged to regulate the flow of a fluid through a port, including a corrugated bellows having a movable end and a relatively fixed end,

means supporting said valve member from said movable end, said bellows being evacuated to an internal depression such that the internal gas pressure thereof is less than external pressures over a substantial portion of the altitude range, spring means of such force as to balance the bellows against external pressures at ground level barometer, said valve member being formed with a slot in one of its walls adapted to by-pass said port should the bellows project itself abnormally due to bellows failure at a high altitude.
